BOAT PROPELLING MEANS

Cecil John Nock, Brooklyn, N. Y.

Application May 12, 1932. Serial No. 610,794

6 Claims. (Cl. 115—28)

This invention relates to boat propelling means and in particular to one especially adapted to toy boats, small boats and large vessels, more particularly to inboard and outboard motors and arranged to operate by the movement of a vane to carry out the propelling action.

A most important object of my invention is to provide means whereby the drive may be reversed without changing the direction of drive of the engine or motive power means, it being possible in the case of toy boats to change the direction of propulsion without stopping the motor.

A still further and equally important object of my invention is to provide a yieldable spring device between the driving means and the propeller member which will permit change of direction of propulsion without altering the direction of rotation of the power member and which will be equally efficient when applied to small toy boats as well as larger vessels.

A still further object of my invention is the provision of driving blades which make for more efficient drive than is obtained through the use of the ordinary screw propeller, the blades affording a more direct drive as the blades in their propelling action travelling from a beam to aft and one or more are employed while the other blades are returning to the drive starting position. The propelling agent is so arranged that its action will be reversed when reverse drive of the vessel is desired and the full driving action of the vanes will be taken advantage of in either forward or rearward propulsion. Use may also be made of a plurality of blades mounted at right angles to each other so that when one blade is travelling from a beam to aft, the other blade goes from aft to a beam and provides a more continual form of propulsion than a single bladed driver.

Changes and variations may be made in the construction shown and described without departing from the principles of the invention or sacrificing its chief advantages; hence such invention is not to be confined to the structures shown in the accompanying drawing, in which;

Figure 1 is a plan view of a boat propelling means constructed in accordance with my invention, the covering being omitted for the purpose of illustrating the working parts of my invention.

Figure 2 is a view in elevation of the propelling means illustrated in Figure 1 showing the relative arrangement of the parts and how the device may be operated as an outboard motor.

Figure 3 is a diagrammatic illustration showing the position of the driving vane when the

same has been thrown to position to provide a reverse drive, the yieldable spring member being shown in its squeezed position or the position it would assume during the change from forward to reverse drive of the mechanism parts.

60

Figure 4 is a top plan view of a propelling member employing a plurality of blades, the position illustrated being at a point during the travel of the blades in a propelling movement.

65

Figure 5 is a section taken on the line 5—5 of Figure 4 illustrating the construction of the blade holding frame.

Figure 6 is a plan view of a modified form of propelling member.

70

Figure 7 is a view in elevation of the propeller illustrated in Figure 6.

75

Referring to the drawing in detail, 5 indicates a vessel of any description, toy or otherwise, on which is mounted a frame 6 in which is supported, the propelling agent driving mechanism, it being understood that the illustration of the device is in connection with toy boats and hence a spring operated motor is employed but it is to be distinctly understood that the drive shaft of the mechanism can be driven from any suitable source of power such as an engine of the type employed in marine vessels, without altering the scope of my invention.

80

In the frame 6 is journaled the key wind shaft or stem 7, one end of which is squared for the reception of a winding key whereby the spring 8 having one end attached to said stem 7 and the opposite end attached as at 9 to the frame 6 may be wound up preparatory to driving the drive gear 10 mounted on the shaft 11. This gear 10 meshes with a pinion 11 mounted on a shaft 12 which, in turn, carries the gear 13 meshing with a pinion 14 on the shaft 15. This shaft 15 also carries the gear 16 which meshes with and drives the pinion 17 mounted on the main drive shaft 18. The main drive shaft 18 extends above the casing 6 and is provided with an eccentric portion 19 to which is secured one end 20 of a drive and reversing bar 21 whose center portion is C-shaped as at 22, provided at one side with an opening 23 so that, as illustrated in Figure 3, the C portion 22 may yield when the eccentric portion 24 of the vertical propeller shaft 25 is revolved through the medium of the handle 26 to change the direction of drive of the vessel.

90

The end of the member 21 is connected to the eccentric portion 24 and is arranged to oscillate the same through an arc of 90 degrees, as illustrated in Figure 1, while the eccentric 19 of the

95

means 21 is connected to the eccentric portion 24 and is arranged to oscillate the same through an arc of 90 degrees, as illustrated in Figure 1, while the eccentric 19 of the

100

end of the member 21 is connected to the eccentric portion 24 and is arranged to oscillate the same through an arc of 90 degrees, as illustrated in Figure 1, while the eccentric 19 of the

105

110

drive shaft 18 revolves in one direction continuously. The upper end of the shaft 18 is provided with a fly wheel 27 for the purpose of carrying the eccentric drive member 21 over its 5 points of dead center. In driving the mechanism by motor power or from an engine, the gearing and spring mechanism described would be dispensed with and the drive to the main drive shaft 18 would be taken directly from the source 10 of power in any suitable and well known manner.

The shaft 25 is supported in suitable brackets 28, its lower end being beneath the surface of the water and, as illustrated in Figure 2, is curved as at 29 to provide the upstanding portion 30 on which is pivoted, the vane 31 provided with the ears 32 which encompass the upstanding portion 30 of the shaft and permit free swinging movement of the vane 31 back and forth as the shaft 25 is oscillated by the eccentric 20 drive member 21. The swinging movement of the vane 31 is arrested by the vane limit plate 33 which is secured to the shaft 25 and is provided with the V-shaped cut-out 34 against the edges of which the vanes 31 move. From inspection of Figure 1 it will be noted that when the vane 31 is oscillated, it will push the water sidewise and rearwardly to provide a forward drive for the vessel and when the handle 26 is operated to snap the shaft 25 to position the 30 vane as illustrated in Figure 2 and Figure 3, to provide a reverse drive, the vane will be oscillated through an arc of 90 degrees to provide for a reverse drive of the vessel.

In the construction illustrated in Figures 4 and 35 5, the drive shaft 25 may be provided with the vane frames 36 and 37 in the form of V-shaped plates which are secured in any suitable manner to the shaft 25 and at their outer ends support the pins 38 and 39 to which, through the medium 40 of the ears 40, are hingedly connected, the vanes 41 and 42. The shaft 25 also carries midway between the vane frames 36 and 37, the V-shaped vane limiting plates 43, the outer ends of whose extended portions are cut out as at 45 to permit 45 free movement of the vanes 41 and 42 through an arc of approximately 120 degrees, it being understood that the movement of the blade or vane 31 will be limited by the cut-out 45 which may be of any degree deemed desirable for the 50 efficient operation of the vane.

In Figure 4, the center line of the vessel is illustrated and it is quite evident that oscillation of the shaft 25 as described in connection with the mechanism illustrated in connection 55 with Figures 1 to 3 will cause oscillation of the frame members 36 and 37 through an arc of substantially 90 degrees, although this may be varied if deemed desirable and when one of the vanes 41 is travelling from abeam to aft, the 60 other travels from aft to abeam, thus providing a more continual form of propulsion than is possible with the use of a single blade or vane 31.

In the modified forms of my invention illustrated in Figures 6 and 7, use is made of a vane 65 holder 50 secured to the shaft 25 and arranged to oscillate therewith and arranged to hold a vane shaft 51 upon which the vane blade 52 is

mounted for free swinging movement, the movement being limited by the vane stop plate 53 which is secured to the frame 50 and is provided with the forked end 54 to limit the swinging movement of the blade 52. The extended portion 55 of the vane frame 50 is arranged to have journalled therein, the shaft 56 to which is secured the vane 57 whose extended upper and lower edges 58 are positioned between the bifurcated ends 59 of the upper and lower portions 85 of the frame 50.

My invention is not to be restricted to the precise details of construction shown since various changes and modifications may be made therein without departing from the scope of the 90 invention or sacrificing the advantages derived from its use.

What I claim is:—

1. In a device of the character described, an eccentric drive shaft, means for revolving said shaft, an oscillating propeller shaft, a connector joining said drive and propeller shaft and means in said connector for yieldably permitting change of position of said propeller shaft whereby it may oscillate in different positions. 100

2. In a device of the character described, a drive shaft, means for revolving said shaft, a propeller shaft, means for eccentrically connecting both of said shafts whereby the propeller shaft will oscillate, and a compressible means in said 105 connecting means for permitting the propeller shaft to be snapped from one driving position to another.

3. In a device of the character described, a revolving drive shaft, an oscillating propeller shaft, 110 a driving connector between said shafts, and a yieldable section in said driving connector for permitting the propeller shaft to be snapped from one driving position to another.

4. In a device of the character described, a revolving drive shaft, an oscillating propeller shaft, 115 a yieldable driving connector between said shaft, a driving vane hinged to said propeller shaft to permit the propeller shaft to be moved from one driving position to another, and a member for engaging the vane to limit the swinging movement thereof when the propeller shaft is oscillating. 120

5. In a device of the character described, a revolving drive shaft, an oscillating propeller shaft, a driving connector between said shafts, a driving 125 vane hinged to said propeller shaft, a member for engaging the vane to limit the swinging movement thereof when the propeller shaft is oscillating, and a yieldable section in said driving connector for permitting snap movement of the 130 propeller shaft to position the driving vane for forward or rearward driving action.

6. In a device of the character described, a revolving drive shaft, an oscillating propeller shaft, a driving connector between said shafts, a yieldable section in said driving connector for permitting the propeller shaft to snap from one driving position to another, and a handle on the upper end of said propeller shaft whereby said snap movement may be imparted thereto without stopping 140 the action of the mechanism.

CECIL JOHN NOCK. [L.S.]
